DESIGN FOR A FISH LURE

William H. Schaper, Robbinsdale, Minn.

Application August 4, 1939, Serial No. 86,461

Term of patent 14 years

To all whom it may concern:

Be it known that I, William H. Schaper, a citizen of the United States and residing in the city of Robbinsdale, county of Hennepin, and State of Minnesota, have invented a new, original, and ornamental Design for a Fish Lure, of which the following is a specification, reference being had to the accompanying drawing, forming a part thereof, wherein:

Fig. 1 is a top plan view of a fish lure showing my new design;

Fig. 2 is a side elevation thereof;

Fig. 3 is a front elevation; and

Fig. 4 is a rear elevation.

Portions of the drawings are lined to indicate contrasting colors.

I claim:

The ornamental design for a fish lure, as shown and described.

WILLIAM H. SCHAPER.
